UNITED STATES PATENT OFFICE.

ALBERT BLANKENHAGEN, OF AKRON, OHIO, ASSIGNOR OF ONE-HALF TO FRANK W. BLANKENHAGEN, OF AKRON, OHIO.

DESIGN FOR A CASING FOR LIQUID-PISTOLS.

47,099.

Specification for Design.

Patented Mar. 16, 1915.

Application filed November 3, 1914. Serial No. 870,159. Term of patent 14 years.

To all whom it may concern:

Be it known that I, ALBERT BLANKENHAGEN, a citizen of the United States, residing at Akron, in the county of Summit and State of Ohio, have invented a new, original, and ornamental Design for Casings for Liquid-Pistols, of which the following is a specification, reference being had to the accompanying drawing, forming part thereof.

The figure presented is a side elevation of

a liquid pistol casing, showing my new design.

I claim:

The ornamental design for a casing for a liquid pistol, as shown.

ALBERT BLANKENHAGEN.
